Primary Examiner — Elizabeth J Oswecki(74) *Attorney, Agent, or Firm* — Zhihua Han; Wen IP LLC(57) **CLAIM**

The ornamental design for a crampon for footwear, as shown and described.

DESCRIPTION

FIG. 1 is a top, front, and left side perspective view of a crampon for footwear, showing my new design;
 FIG. 2 is a front elevation view thereof;
 FIG. 3 is rear elevation view thereof;
 FIG. 4 is a left side elevation view thereof;
 FIG. 5 is a right side elevation view thereof;
 FIG. 6 is a top plan view thereof;
 FIG. 7 is a bottom plan view thereof;
 FIG. 8 is a top and left side perspective view; and,
 FIG. 9 is a top and right side perspective view.
